UNITED STATES PATENT OFFICE.

ARTHUR LEE LIGON, OF KILLEEN, TEXAS.

DEMOUNTABLE HEADSTOCK FOR LATHES.

1,422,994.

Specification of Letters Patent. Patented July 18, 1922.

Application filed May 3, 1920. Serial No. 378,620.

To all whom it may concern:

Be it known that I, ARTHUR LEE LIGON, a citizen of the United States, and a resident of Killeen, in the county of Bell and State 5 of Texas, have invented certain new and useful Improvements in Demountable Headstocks for Lathes, of which the following is a specification.

My invention relates to improvements in 10 turning lathes, it being more particularly in the nature of an improved head stock which may be attached or detached to or from any of the existing types of small or large lathes.

A further and more important object of 15 the invention is to provide an improved head stock which is attachable to any of the ordinary types of small or large lathes, it being especially constructed to enable the taking of work which would otherwise be far too large 20 and cumbersome for the lathe to take.

More specifically stated, a further object 25 of the invention is to provide a head stock, applicable to that type of small turning lathe ordinarily found in machine shops, of such construction to enable the taking of drill stems and other long work to be worked on, such drill stems being far too long to be 30 taken by the small lathe according to the ordinary and usual arrangements.

35 A further object of my invention is to provide a head stock of such construction which enables extremely long drill stems to be taken by the ordinary types of small lathes for repair operations, which lathes are ordinarily totally incapable of taking such stems, without cutting the drill stems and necessitating subsequent welding.

40 Other objects and advantages will appear in the following specification, reference being had to the accompanying drawings, in which:—

Figure 1 is a side elevation of a conventional type of small lathe with the improved demountable head stock applied thereto.

45 Figure 2 is a plan view of the mechanism shown in Figure 4,

Figure 3 is a central longitudinal section of the lathe and head stock attachment, portions of the lathe being shown in elevation,

50 Figure 4 is a cross section on the line 4—4

of Figure 1, illustrating the reversing mechanism.

Figure 5 is a detail side elevation of the head stock attachment, as it appears when constructed in readiness for sale on the 55 market,

Figure 6 is a detail longitudinal section taken substantially on the line 6—6 of Figure 2,

Figure 7 is a cross section on the line 7—7 60 of Figure 1,

Figure 8 is a detail perspective view of the reversing gear housing,

Figure 9 is a detail side elevation of a 65 modification of the end stock attachment, which embodies features of universal adjustability which are not disclosed in the form shown in Figure 5, and

Figure 10 is a detail cross section on the 70 line 10—10 of Figure 9.

As stated above, the improved head stock is manufactured and marketed as an attachment applicable particularly to small lathes, such as for example is illustrated in Figure 1. Generally described, the lathe comprises 75 the lathe bed 1 with the live head stock 2 at the left end.

The usual face plate or chuck which accompanies the small lathe, is removed from the driven spindle 3 and the large drive gear 4 of the improved head stock attachment is screwed in its place on the threaded end 5 of the spindle. The tool carriage 6 is suitably mounted on the lathe bed, and extending longitudinally of the bed is a fixed rack 7 85 along which the head stock attachment is adjusted in the manner disclosed below.

The attachable head stock 8 comprises a cylindrical body or barrel 9 which revolves in the bearings 10 of the main frame 11 by 90 means of the driving connections shown in Figure 2. These connections comprise head stock gears 12 and 13 on the respective ends of the barrel 9, and driving pinions 14 and 15 on the transmission sleeve 16. 95

As indicated in Figure 6, the sleeve 16 is hollow but arranged to support the transmission shaft 17, in respect to which the sleeve and the entire head stock 8 is 100 slideable. A universal joint 18 at the left end

of the shaft 17 joins a connection 19 and a second universal joint 20 to the spindle 21 of the driven pinion 22.

Normally the pinion 22 meshes with the main drive gear 4 to cause the rotation of the barrel 9 in one direction through the medium of the driving connections just described, but the idler pinion 23 may be shifted into engagement with the main gear 4 in order to reverse the direction of rotation of the barrel. The reversing mechanism includes the housing 24, which has bearings 25 and 26 in which the spindle 21 of the pinion 22 and the shaft of the idler 23 are respectively journalled.

A handle 27 with a spring detent 28 cooperates with a quadrant 29 in positioning the housing 24 in either the forward, neutral or reverse positions as designated by the three notches respectively indicated 30, 31 and 32. When the housing is shifted so that the detent occupies the upper notch 30, then the mechanism is in the normal running position. When the middle notch is occupied, the parts are in the neutral position; and when the lower notch 32 is occupied, the idler 23 engages the main gear 4, and the parts are in the reverse running position.

30 A stud 33 at one side of the housing 24, provides the pivotal mounting for the housing in a block 34 which is adjustable in the slot 35 of a bracket 36 by a screw 37. The bracket 36 is practically a part of the base 38 which is fixed on the guide 39 of the lathe bed 1, by means of the clamp plate 40 and bolt 41. Although the bracket 36 is fixed in respect to the lathe bed 1, it may be adjusted for various positions, when necessary, in respect to the main gear 4.

Returning now to the head stock: There is a spline and groove connection 42, 43 between the transmission sleeve and shaft 16, 17, the groove running the full length of the shaft so as to enable the sliding of the head stock 8 practically to the end of the transmission shaft. A chuck 44 at the inner end of the barrel 9, has jaws 45 for holding the adjacent end of the work 46, and a second chuck 47 at the right end of the barrel 9 has centering screws 48 for centering and supporting the work coaxially of the barrel.

Both chucks together with the adjacent gears 12 and 13 are securely fixed on the barrel 9 by means of the keys 49 or other equivalent means. The main frame 11 is clamped in various positions on the lathe bed 1 by means of the clamp plate 50 and bolt 51, but it is to be observed that the base of the frame 11 is formed to easily slide on the guides 38 of the bed in the event that the bolts 51 are unloosened to enable other adjustments of the head stock 8.

Movement of the head stock 8 along the

lathe bed 1 when the clamping connections 50, 51 are unloosened, is obtained by means of turning the crank 52 journaled on the bracket 53 of the main frame 11, which in turn causes the rotation of the adjusting pinion 54 so that the movement of the head stock results through the running of the pinion along the rack 7. I-bolts 55, carried by the caps of the journals 10, enable the application of the hoisting apparatus 56 when it is desired to lift the head stock 8 either on or off of the lathe bed 1.

The modification in Figures 9 and 10, instead of consisting of a practically solid main frame 11, comprises a main frame 11^a which is laterally adjustable on the intermediate base 57, which in turn is capable of vertical adjustment in respect to the lathe bed 1, by means of adjustable wedge bases 58. Lateral recesses 59 in the main frame 11^a, make room for the I-clamp bars 60, the lower ends of which occupy the inverted T grooves 61 in the intermediate base 57.

When the nuts of the clamp bolts 62 are unloosened so that the I-bars 60 release their clamping engagement with the intermediate base 57, the adjusting screw 63 is to be actuated so as to convey the main frame 11^a laterally of the base 57. On the same principle, the adjusting screw 64 is turned so as to move the wedge bases 58 either inwardly or outwardly in respect to the intermediate base 57, the contacting inclined surfaces causing either the up or down movement of the structure supported on the wedge bases.

It is thus to be observed that the head stock 8^a in Figure 9 is universally adjustable, the arrangement therein embodied being very desirable for obvious reasons. In its other respects, the modified head stock 8^a is of the same construction as that in Figure 3.

The advantages and operation of the invention may be briefly reviewed to advantage. It is to be borne uppermost in mind that the head stock 8 in Figure 5 is sold as an attachment to any of the ordinary types of small or large lathes usually to be found in machine shops. The head stock attachment makes it possible for the lathe to take work which is longer than the lathe bed.

The ability to do this is of especial value in the oil fields, where repairs are often required to be made to drill stems, such as indicated at 46 in Figure 3, which runs from four to fifty feet in length.

The prevalent practice in repairing drill stems which are too long to be accommodated by a small lathe, is to cut the drill stem to such a length as to include the part which requires repairing and to enable the insertion of that part in the lathe. After the repair is made, the two parts of the drill stem or other long work must be welded

again, but it often occurs that the weld is imperfect so that in the subsequent operation of the drill stem, it breaks at the weld and an expensive fishing operation is the result.

5 By using the improved head stock, drill stems which could never have been accommodated without cutting, as described above, may be accommodated in a small lathe, the front and rear chucks adequately supporting the work so that the repairing or turning operation may be performed with perfect ease and satisfaction. The reader will understand the manner of operation very readily in connection with the foregoing, all 10 that is required being the insertion of the work 46 into the barrel 9, tightening the jaws 45 of the front chuck and centering the work by adjusting the centering screw 48.

The lathe is started in the ordinary manner and the turning operation can be carried out according to requirements. It is of course obvious by considering the drawings, that the ordinary lathe tail stock and center rest have been removed so as to admit of 25 locating the improved head stock 8. The head stock 8 may be described or illustrated as a cradle support which at once sustains the work over a relatively long base and at the same time turns it in respect to the turning 30 tool.

While the construction and arrangement of the improved attachable head stock as herein described and claimed, is that of a generally preferred form, obviously modifications and changes may be made without departing from the spirit of the invention or the scope of the claims.

I claim:—

1. An attachment for common lathes enabling turning work longer than the lathe bed, comprising a hollow head stock in substitution of the usual tail stock and center rest, drive means for said head stock in connection with the lathe spindle, and means 40 embodied in said drive means compensating for differences in location of the latter and of the head stock.

2. An attachment for lathes enabling turning operation on work longer than the lathe bed, comprising in combination with the driving spindle and head, a main gear applied to the spindle, a main frame on the bed, with journals supporting a barrel with work gripping and centering means on each 50 end, and a driven element fixed adjacently to each gripping means, with driving connections extending to the main gear.

3. An attachment for lathes enabling the performance of turning operations on work 60 longer than the lathe bed, comprising in combination with the driving spindle and bed, a main gear suitably applied to the spindle, a main frame adjustable to various clamped positions on the bed, a barrel sup-

ported by the frame, with means at one end 65 for gripping and at the other end for centering a piece of work axially of the barrel; and driving means between the barrel and main gear, including driven elements applied to the barrel at a plurality of places to secure a uniform rotational torque, and associated driving elements mounted on a sleeve with a telescopic splined shaft with universal joint connections to a pinion engaging the main gear. 75

4. An attachment for lathes enabling the performance of turning operations on work longer than the lathe bed, comprising in combination with the spindle and bed, a main frame with means for clamping it in adjusted 80 positions along the bed, a barrel journaled on the frame, with each-end gripping means for supporting the work coaxially of the barrel, and adjacently carried driven gears for distributing the driving torque; 85 a transmission sleeve journaled on the frame, with driving means engaging the gears; a transmission shaft splined and telescoped in the sleeve to maintain the driving connection regardless of the main frame positions, a 90 main gear on the spindle, and shaft driving means including a normally engaging pinion, in a housing pivoted on a bracket with a notched quadrant for the engagement of a detent in a handle on the housing, for obtaining either a forward drive, a neutral position, or a reverse drive, by shifting the 95 housing, to bring an idler in the frame in engagement with the main gear.

5. The combination of a barrel, with 100 means for gripping an axially rotated piece of work, and a main gear from which the barrel is rotated; and intermediate driving connections including a telescopic shaft enabling a change of position of the barrel in 105 respect to the main gear without severing the driving connections.

6. A head stock attachment for lathes, including a driving pinion bracket on a base with means for clamping it on the guides 110 of the lathe bed; and a work holder-supporting main frame adjustably slidable on the bed guides, but provided with fastening clamp means including bolts and clamp plates. 115

7. In combination with the guides of a lathe bed and a longitudinal rack, of a head stock attachment slidable on said guides but provided with clamp means for fixing it in various positions, including a bracket-supported cranked-pinion engaging the rack for moving the head stock to desired positions when the clamped means is unloosened. 120

8. A universally adjustable head stock attachment for lathes, comprising a main 125 frame, and an intermediate base with means enabling lateral adjustment of the main frame thereon; and wedge bases beneath the

intermediate base, with means enabling vertical adjustment thereof by moving said wedges.

9. A universally adjustable head stock attachment for lathes, comprising a main frame with transverse recesses, and I-bars partly occupying the recesses, with clamp bolts; an intermediate base with inverted T-slots occupied by the remainder of the

I-bars, with inclined end surfaces, and adjusting means enabling the lateral adjustments of the main frame; and a base wedge beneath each inclined surface, with means enabling longitudinal adjustment to raise and lower the structure imposed on the base wedges.

ARTHUR LEE LIGON.
